UNITED STATES PATENT OFFICE.

JAMES GERRY WALKER, OF HUDSON, NEW HAMPSHIRE.

ROLL-TOP BOX.

SPECIFICATION forming part of Letters Patent No. 354,277, dated December 14, 1886.

Application filed November 1, 1886. Serial No. 217,689. (No model.)

To all whom it may concern:

Be it known that I, JAMES GERRY WALKER, of Hudson, in the county of Hillsborough, of the State of New Hampshire, have invented a new and useful Improvement in Boxes; and I do hereby declare the same to be described in the following specification, and represented in the accompanying drawings, of which—

Figure 1 is a top view, Fig. 2 is a transverse vertical section, and Figs. 3 and 4 are longitudinal, vertical, and horizontal sections, of a roll-top box of my invention, the nature of which is defined in the claims hereinafter presented.

15 In such drawings, A denotes the box-body, and B its cover, such body having within it three chambers, a, b, and c. The first one, or that marked a, is the main chamber of the box. At one end of it is the chamber b, which at its 20 lower part opens into the chamber c, extending underneath the bottom d of the main chamber a, and from end to end and side to side of the box-body. The two opposite sides of the body A are grooved near and parallel with 25 their upper edges, the grooves being shown at e. These grooves are continued, or each opens into one of two semicircular grooves, f, at the opposite ends of the end chamber, such grooves f opening at their lower ends into the chamber c.

The cover B is a flexible one, it being composed of a strip, g, of leather, cloth, or other suitable material, and a series of strips, h and i, of wood, laid edge to edge and glued or fastened to such strip g, each strip h having a transverse section, which is the segment of a circle. The strip i, which is at the outer end of the series, is deeper than each of the others, or extends above them, and there is directly underneath and fastened to the strip h, which is next such strip i, another or a stop strip, k, which is fastened to the flexible strip g, and serves, when the cover is closed, as a

stop to prevent it from being drawn out of the box. The cover so made is inserted within 45 the grooves e, and may be slid or moved backward therein, so as to cause it (the said cover) to pass more or less down the end chamber, b, into the lower chamber, c, for the purpose of opening the box. On the cover being 50 pulled forward, so as to bring the stop-strip k up to the anterior end of the box, such box will be closed. There may be a lock fixed in the said end, and there may be in the strip i a recess to receive the bolt of the lock when 55 such bolt is advanced or moved upward by a key.

I am aware that desks have been made with what are termed "roll tops," and therefore I do not claim such, in which case there was but 60 a single chamber for the top to pass down into; but in my box-body there are besides the main chamber two others, one being underneath the bottom and the other in rear of the said main chamber.

I claim—

1. The combination of the box-body A, provided with the main and two auxiliary chambers, a, b, and c, and having the straight and semicircular grooves e and f arranged therewith, as described, with the roll top or cover B inserted and to work in such grooves, and constructed substantially as set forth.

2. The combination of the box-body A, provided with the main and two auxiliary chambers, a, b, and c, and having the straight and semicircular grooves e and f arranged therewith, as described, with the roll-top cover B, as explained, furnished with the stop-strip k and inserted and to work, as explained, in 80 such grooves, all being substantially as represented.

JAMES GERRY WALKER.
